UNITED STATES PATENT OFFICE.

THOMAS T. KNIGHT, OF BROOKLYN, NEW YORK.

DESIGN FOR A PICTURE-FRAME.

Specification forming part of Design No. **11,201**, dated May 13, 1879; application filed April 15, 1879.
[Term of patent 3½ years.]

To all whom it may concern:

Be it known that I, THOMAS T. KNIGHT, of Brooklyn, Kings county, State of New York, have invented a new and original Design for a Picture-Frame, of which the following is a specification.

The accompanying photographic illustration represents a perspective view of my newly-designed picture-frame.

This invention relates to a new and original design for a picture-frame.

It consists of the several details of invention, hereinafter pointed out.

The body A of the picture-frame has a horseshoe-shaped outline and a straight base, a. The inner opening, B, of the frame is made of the same horseshoe-shaped outline as the frame, and has a straight bottom, b, and curved sides and top. Between the outer part of the outer frame, A, and the inner opening, B, is placed against the face of the frame a horseshoe-shaped ornament, C, which extends around the curved part of the opening B.

The frame A may be ornamented by suitable embellishments, and the horseshoe C may

be provided with floral or other design, as shown.

I claim—

1. The design for a picture-frame, A, having the outline of a horseshoe and straight base a, substantially as shown.
2. The design for a picture-frame, having a sight-opening, B, shaped like a horseshoe, with a straight base, b, substantially as shown.
3. The design for a picture-frame, having a horseshoe-shaped ornament, C, around the sight-opening B, substantially as shown.
4. The design for a picture-frame of the following configuration, namely: which is curved at the top and sides, at the inner and outer edges, and is straight at the lower edges, a and b, substantially as shown.
5. The design for a horseshoe-shaped picture-frame, having a horseshoe-shaped ornament, C, substantially as shown.

THOS. T. KNIGHT.
